UNITED STATES PATENT OFFICE

ISRAEL E. HELLER, OF BUFFALO, NEW YORK

WOVEN FABRIC

Application filed December 18, 1928. Serial No. 326,723.

The objects of this invention are to provide a fabric with means at the edges thereof for indicating the directions in which the filling threads of the fabric extend at intervals 5 lengthwise of the fabric; also to improve woven fabrics in other respects hereinafter specified.

In the accompanying drawings:

Fig. 1 is a face view of a portion of a strip 10 of woven fabric embodying this invention.

Fig. 2 is a face view of similar fabric folded over along the line midway between the selvages of the fabric.

Fig. 3 is a face view of a length of a piece 15 of woven fabric, the view being provided with lines to indicate the directions of the cross or filling threads of the fabric.

Fig. 4 is a view of the fabric shown in Fig. 3 when folded on a line approximately 20 midway between the selvages.

Fig. 5 is a face view of two corresponding portions of a garment cut from fabric having cross threads therein running in different directions.

25 In the manufacture of garments, such as suits from woolen or worsted fabrics, trouble is frequently experienced after the cutting of the cloth according to patterns, with the "jumping" or changing of shape of the parts 30 after cutting. The cloth from which two corresponding parts of a suit are cut is generally folded along a longitudinal central line and in cutting the cloth from a pattern, two parts are cut at the same time.

35 With certain kinds of cloth this "jumping" which takes place after the cutting, results in the two parts assuming different forms from the original pattern. This is clearly illustrated in Fig. 5 which shows two parts A and A' of a garment, which parts after cutting were separated and then again placed one on top of the other with their edges *a* in alignment. Because of unequal 40 stresses in the cloth itself, these two parts of the garment assume the shapes indicated although both parts were cut from the same pattern and at the same time and from directly opposite sides of the same piece of goods.

This "jumping" of the cloth after cutting

is a source of large expense to manufacturers of garments, since in many cases the parts of the cloth become distorted to such an extent that they cannot be used in the manufacture of a garment, without having the garment 55 itself misshaped or distorted.

Investigations as to the cause of this "jumping" has disclosed the fact that it is due mainly to unequal stresses in the cloth caused by the cross or filling threads extending in different angles in different parts of the cloth. In order to prevent this "jumping" of parts of the cloth after cutting, the cloth must be woven with the filling threads extending exactly at right angles to the longitudinal or warp threads. In most looms now used, this condition can be easily complied with but woolen or worsted fabric must be subjected to other processes after weaving, which processes tend to stretch the cloth at various points or edges, or to shrink the edges at other points so that there is a tendency in the cloth to distortion.

Cloth is frequently distorted during the process known as "tenting" to which the cloth is subjected after shrinking the same to give the same the desired uniform width.

The usual form of "tenting" machine includes two endless chains spaced at the desired distance apart depending upon the width desired, on which chains are mounted pins to which the selvages of the cloth are attached while the cloth is being stretched to the desired width. This endless chain carries the cloth through a drying apparatus and if the cloth is not attached to the various pins in such a manner so that all cross or filling threads extend exactly at right angles to the length of the cloth, the cloth will be stretched on one side and contracted on the other. This may occur a number of times in a single piece of cloth and when such cloth is thoroughly dried, it appears to be straight and it is impossible to detect the stretched or contracted portions of the fabric, since the cross or filling threads are usually not clearly visible. When such cloth is folded along a longitudinal central line, it may appear to be perfectly even, but when parts of the garments are cut out of the cloth, these parts will re-

sume their natural shapes for the reason that the tension or stretch is released by cutting, and the result is that the cut out parts will not correspond to the pattern from which they are cut. These conditions are not always eliminated by the fact that the clothing manufacturers subject the cloth to a steam or water shrinking process before cutting it into garments. In many cases this shrinking process will allow the cloth to come back in its original woven condition, while wet, but on being again dried and folded, there is again a possibility of the edges becoming distorted, thus leaving the cloth in the same uncertain condition in which it left the mill.

Figs. 3 and 4 illustrate the manner in which woolen and worsted fabrics may be distorted. The strip of cloth B in this case has the filling threads near the upper edge arranged correctly at right angles to the length of the cloth, as indicated by the direction line 10.

The direction lines 11 immediately below the top edge of the cloth are inclined with reference to the line 10. The direction lines 12 indicate the filling threads extending at a different inclination, and the angles of these threads are again alternately reversed as indicated by the lines 13 and 14 respectively. If these lines were actually present on a strip of cloth, it could of course be readily stretched and shrunk to cause all these lines to become parallel, but in plain colored goods or in goods having small checks or stripes running only lengthwise, the directions of the filling threads cannot be determined except at the two opposite ends of the cloth.

When cloth of this kind is folded, as is the custom before the same is cut, the filling threads will be arranged as shown clearly in Fig. 4, extending in different directions in the two folded halves of the cloth. Consequently when parts of a suit are cut from cloth of this kind, the threads in the cut parts tend to straighten themselves out to their normal positions, thus causing the two cut parts to "jump" in opposite directions from the original pattern, so that a correct garment could not be made from such parts.

In accordance with my invention, the cloth is provided during the weaving thereof with indicators on the selvages thereof which are arranged in pairs spaced directly opposite each other, each pair being arranged at opposite ends of a filling thread, and these pairs of indicators are arranged at intervals lengthwise of the fabric and spaced sufficiently far apart so that the operatives handling the cloth can readily determine which two indicators at opposite sides of the cloth belong to the same pair. The pairs of indicators may be arranged at longer distances apart since it is not necessary to check the cloth at very close intervals in order to prevent distortion in the cloth.

These indicators may be provided at opposite ends of the filling threads in any suitable or desired manner. For example, the indicators may be provided by causing the shuttle carrying the filling thread to travel at certain intervals through distances slightly beyond the selvage, thereby leaving loops of thread at opposite ends of a single travel or stroke of the shuttle. This operation of the shuttle may be repeated at intervals lengthwise of the cloth to space the indicators or loops at the desired distances apart. Instead of providing a loop indicator consisting of a single loop, a plurality of loops could be formed on a number of adjacent filling threads, by causing the shuttle on several successive strokes to leave loops beyond the selvage. Any other means for providing indicators of this kind at or beyond the selvage of the cloth may be used if desired.

In Figs. 1 and 2, C represents a length of cloth having a series of projecting threads or indicators c extending beyond one selvage of the cloth and corresponding indicators c' extending beyond the other selvage. When this cloth is folded along a longitudinal central line, the indicators c and c' will lie in registration when the filling threads extend exactly at right angles to the length of the cloth. 20 and 21 represent the opposite selvages of the cloth and in Fig. 2, 22 represents the folded edge thereof. When cloth of this kind is placed on a tentering machine, the operatives can readily place the same on the machine so that the filling threads extend at right angles to the length by observing the indicators c and c' on the selvage and positioning the same at exactly opposite portions of the endless chains. Similarly a clothing manufacturer, in placing the cloth on a roll after shrinking, can compare the positions of the indicators with relation to guide lines or straight edges on the roll, and in the event that the indicators show incorrect relationship of the filling threads, such condition can be corrected or the cloth rejected for use in garments.

By the use of cloth of this kind and by the described process of preventing distortion therein by the correct arrangement of the filling threads, the "jumping" of cloth after cutting can be either entirely eliminated or very materially reduced, thereby effecting a large saving on the part of garment manufacturers, as well as improving the quality of the garments made from such cloth. Furthermore cloth made in accordance with my invention is no more expensive to produce than cloth heretofore made, since the determining of the correctness of the filling threads can be done at a glance, while in the step of tentering, the indicators facilitate the placing of the cloth on the endless chains. Cloth provided with these indicators is not in any way damaged or in-

jured thereby since in the cutting of the cloth, the portions thereof on which the indicators are formed are not used as parts of the garments.

5 Claims:

1. A woven fabric having filling threads, some of which have portions visible on both sides of the fabric at the side edges thereof to indicate the opposite ends of a filling thread, said projecting portions being arranged at substantial distances from each other, to indicate the directions in which the filling threads extend.

10 2. A woven fabric having some of its filling threads, at substantial distances lengthwise of the fabric, provided with portions projecting beyond the side edges of the fabric at opposite ends of a transverse length of filling thread, to indicate the directions in which the filling threads extend.

15 3. A woven fabric having indicating parts at the opposite edges thereof at opposite ends of a filling thread and positioned at substantial distances from each other lengthwise of the fabric, to indicate the directions in which the filling threads extend.

20 4. A woven fabric provided with indicators on the selvedges thereof, said indicators being readily visible from both sides of the cloth and being arranged in pairs, the two indicators of a pair being arranged at opposite ends of the same filling thread, each pair of indicators being spaced from adjacent pairs at substantial distances lengthwise of the fabric.

25 5. A woven fabric having selvedges at opposite sides thereof, said selvedges being provided with clearly visible indicators arranged in pairs, the two indicators of a pair being arranged at opposite ends of the same filling thread, to enable the direction of the filling thread to be readily determined.

ISRAEL E. HELLER.
